UNITED STATES PATENT OFFICE.

MAURICE C. CLARK, OF FRANKLIN, MASSACHUSETTS.

MOLD FOR CUSHION-HEELS.

1,370,287.

Specification of Letters Patent. Patented Mar. 1, 1921.

Application filed May 13, 1920. Serial No. 381,010.

To all whom it may concern:

Be it known that I, MAURICE C. CLARK, a citizen of the United States, residing at Franklin, in the county of Norfolk, State 5 of Massachusetts, have invented certain new and useful Improvements in Molds for Cushion-Heels, of which the following is a specification.

My invention relates to improvements in 10 the art of manufacturing cushion-heels for shoes and slippers, and particularly to the molds for forming and vulcanizing the heels.

One object of the invention is to provide 15 a mold for forming and vulcanizing a heel having a pronged fastening-element or spider embedded in its structure.

Another object of the invention is to provide means for holding the fastening-element 20 in place during the molding operation to locate it in correct position in the heel.

Another object of the invention is to provide means for holding the fastening-element in such relation in the mold that the 25 ends of its prongs will project from the face of the finished heel when the latter is removed from the mold.

Another object of the invention is to provide means for forming a countersunk 30 screw- or nail-hole in the heel corresponding with a countersunk aperture in the fastening-element.

Another object of the improvement is to provide for a more convenient and easy 35 method of operation of the molding means whereby to facilitate the manufacture of the article in large quantities.

Further objects of the invention will appear from the description of the embodiment 40 of my improved mold set forth in the following specification which is illustrated by the accompanying drawings. In the drawings:

Figure 1 is a sectional view showing one 45 type of attachable heel adapted to be manufactured in my improved mold, and illustrating it as applied to the permanent heel of the shoe;

Fig. 2, a plan view of the heel;

Fig. 3, a perspective view of the heel;

Fig. 4, a plan view of the lower or main portion of my improved mold;

Fig. 5, a cross-sectional view through the mold, taken on the line X—X of Fig. 4; 55 and

Fig. 6, a side view of the top-plate of the mold.

Referring first to Figs. 1, 2 and 3, the type of heel H here shown consists in a top-lift for attachment to the main leather or wooden heel K of the shoe, and particularly for use on ladies' slippers or dress shoes having the so-called "high" or "French" heels. The heel H is usually made of rubber or composition material to 60 provide a cushioning action and is generally marketed as a repair part for replacing the worn top-lift of the original heel on the shoe. In applying such heels to ladies' shoes or slippers having slender heels of 65 wood it is extremely difficult to attach them in place with nails or screws without splitting or breaking the permanent part of the heel on the shoe. To avoid this danger the present type of heel is attached with only 70 one screw or nail S at its center, see Fig. 1, and is held from turning by sharp-pointed spurs or prongs p which project from its attaching face to be indented into the main heel K. As shown in Figs. 1 and 2, the 75 prongs p are formed at the ends of the arms p' which radiate from the center of a metal fastening-element or spider P which is embedded in the body of the heel H. The spider P is provided at its center with a 80 hole h for the nail or screw S which attaches the heel in place, and surrounding the hole is a cupped or countersunk recess r for receiving the beveled head of the nail or 85 screw.

In manufacturing heels of the type above described it has been found a difficult matter to embed the fastening-element in the body of the heel with accuracy and uniformity. The plate or spider P must be 90 located accurately at the center of the heel H and also with exact relation to the attaching face thereof in order that the fastening-prongs p may project the proper distance therefrom. Cushion-heels of this nature are generally molded from rubber or composition in a more or less plastic state and when the material is forced into the mold it will have a tendency to push the fastening-member or spider P out of place 95 unless the latter is held positively against such displacement. One of the principal objects of the present invention is to provide means for supporting the fastening-member P in proper position in the mold in 100 105 110

accurately spaced relation with the walls thereof; and to also lock said member in fixed position to prevent the material entering the mold from forcing it out of place. It is further necessary to prevent the material from filling the recess r of the screw-hole h in the member P and to also provide for forming a recess and apertures communicating with the hole to allow the insertion of the screw therethrough. To accomplish these results while rendering the operation of the apparatus simple and easy to perform and uniformly accurate in its work I have devised the improved mold as next described.

Referring to Figs. 4 and 5 my improved mold comprises two coöoperating parts: a main portion or bottom-member 2 and a cover or top-plate 3, both of which are preferably constructed of metal. Usually the mold is made in "gang" form with its coöperating parts of convenient size to provide for a plurality of heel-cavities, or single molds. For simplification of illustration, however, I have shown a single mold in the drawings, it being understood that the multiple mold is merely a duplication of the single unit.

For convenience of manufacture the main or bottom portion 2 of the mold is usually constructed in two parts comprising flat plates 4 and 5 which are held together by pins or dowels 6, or any other suitable means, see Fig. 5. The lower plate 5 is formed at its center with a raised convex boss 7 which corresponds in outline to the shape of the heel to be molded. The boss 7 is beveled at 8 around its outer edge and serves as a former for the face of the heel lift to be applied against the permanent heel of the shoe to shape it with a slight concavity whereby to adapt it to be more snugly fitted in place. The upper plate 4 is cut away at its center to form a cavity 9 shaped to the outline of the heel and adapted to mold its sides. The sides of the cavity 9 flare outwardly to provide the necessary draft to facilitate the withdrawal of the heel from the mold; and also to mold its sides slightly bell-shaped to conform to the flaring bottom of the permanent heel of the shoe. Surrounding the cavity 9 is a relatively shallow groove or depression 10 for receiving the overflow of material squeezed out of the mold when the cover-plate 3 is pressed down against the top of the bottom section 2.

For supporting the fastening-element or spider P in position in the heel cavity 9 of the mold I provide a central, shouldered spindle or teat 11. For convenience of manufacture the support 11 may be made as a separate element in the form of a pin 12 riveted through a hole in the bottom plate 5. The pin 12 is formed with a flange 13

which abuts the top of the boss 7 on the 65 plate 5 and provides an annular shoulder or ledge with the teat 11 projecting above it. The flange or ledge 13 serves as a rest for the cupped or countersunk central portion of the fastening-member P which is to be 70 embedded in the body of the heel. Surrounding the rest 13 is a row of recesses or depressions 14 cut into the face of the boss 7 and adapted to receive the points of the prongs p on the fastening-member or spider 75 P when the latter is set in place on its seat or support 11.

The cover 3 of the mold consists simply in a flat plate adapted to fit against the bottom portion 2 of the mold and provided 80 with taper-ended dowel pins 15 for engaging holes 16 in the bottom section to guide the cover into place thereon. At the center of the top-plate 3 is a projection or stud 17 adapted to set down against the top of the 85 teat 11 in the cavity 9 with its beveled edge 18 bearing against the sides of the cupped or countersunk depression in the center of the spider P . As shown in Fig. 5, the stud 17 may be formed as the head of a pin 19 90 driven through a hole in the plate 3 and riveted in place therein. Having now described the construction and arrangement of my improved mold, its method of operation will next be explained.

Whether used singly or in series the method of operation of the device is the same. The bottom or main part of the mold is placed on a suitable support, usually in a press, and the fastening device or spider P applied to position in the heel-cavity 9 by setting it on the central spindle or support 11. In setting the spider P in place on its rest 11 the operator rotates it slightly to cause its prongs p to seat in the depressions 14 in the boss 7. The cavity 9 is then filled with the plastic material from which the heel is to be molded and the top-plate 3 brought down against the bottom member 2 to compress the material into a dense mass while molding it to the desired shape. As the top-plate 3 is forced down against the main mold-section 2 its central stud 17 bears against the sides of the depression r in the spider P to hold it firmly on the rest 11, 115 whereby to prevent its displacement by the pressure of the material in the mold. As the cover-plate 3 closes against the bottom-section 2 of the mold the excess material is squeezed out into the overflow groove 10 and 120 the main mass of material in the cavity 9 is compressed into shape around the spider P . In accordance with the usual practice the cover-plate 3 is finally clamped down against the bottom-section 2 and the heel is then subjected to the vulcanizing process to harden the material. After the vulcanizing is completed the cover-plate 3 is removed and the

finished heel may be easily withdrawn by separating the bottom-plate 5 from the plate 4 and forcing the heel out of the cavity 9.

It has been pointed out that the spider P is placed in the mold with its prongs *p* seated in the depressions 14 in the face of the boss 7 so that when the molding and hardening of the heel is completed the points of the prongs *p* will project beyond the face 10 of the heel to adapt them for the purpose above explained. It is also to be noted that the holding stud 17 for the spider P serves as a core for forming an enlarged recess in the bottom face of the heel to accommodate 15 the head of the screw or nail which is inserted through the center of the heel to hold the latter in place. The stud 17 also prevents the material from filling the countersunk recess *r* in the spider which receives the tapered head 20 of the screw S, as shown in Fig. 1; and the flange or rest 11 beneath the spider forms an enlarged opening for the body or shank of the screw. The enlargement of this opening is of advantage as providing a clearance 25 around the sides of the screw so as to allow the heel to be drawn more closely or snugly against the face of the permanent heel to which it is attached.

It will be observed that my invention provides an extremely simple and efficient means 30 for locating and locking the fastening-element or spider P in place in the mold to insure its proper relation in the heel H and to provide for the projection of its fastening prongs *p* beyond the attaching face of the heel.

Various modifications might be made in the structure and arrangement of the parts of the mold without departing from the 40 spirit or scope of the invention; therefore, without limiting myself to the exact embodiment herein shown and described, what I claim is:

1. In a mold for cushion-heels, the combination of complemental mold-sections provided with a cavity for forming the heel, a rest carried by one section within the heel-cavity to adapt it to support a fastening-element to be embedded in the heel, and a 45 clamping-member carried by the other section and adapted to bear against the fastening element to hold it in place on its rest.

2. In a mold for cushion-heels, the combination of complemental mold-sections provided with a cavity for forming the heel, and a rest on one of the sections for supporting a pronged fastening-element to be 55 embedded in the heel, the bottom of the heel-cavity being provided with openings for receiving the points of the prongs of the fastening-element so that the latter will pro-

ject beyond the attaching face of the finished heel.

3. In a mold for cushion-heels, the combination of a lower mold-section, an upper 65 section for coöperating therewith, said sections provided with a cavity for forming the heel and with the bottom of the cavity formed with indentations for receiving the points of a pronged fastening-element to be 70 embedded in the heel, and means projecting into the cavity to engage the fastening-element to hold it in position with its points seated in the indentations.

4. In a mold for cushion-heels, the combination of a lower mold-member having a heel-cavity, a rest in said cavity for supporting a fastening-element to be embedded in the heel, an upper mold-member adapted to set against the lower member to compress 80 the material in the heel-cavity, and means carried by said upper member adapted to bear against the fastening-element to hold it in place on its rest.

5. In a mold for cushion-heels, the combination of a lower mold-section having a heel-cavity, a central spindle projecting upwardly into the heel-cavity and provided with a ledge for supporting a fastening-element to be embedded in the heel, an upper 90 mold-section for coöperating with the lower section, and a stud carried by said upper section and adapted to enter a recess in the fastening-element to engage its sides to clamp it against the ledge on the spindle. 95

6. In a mold for cushion-heels, the combination of complemental sections provided with a heel-cavity for forming the heel, a shouldered spindle projecting into the cavity to engage the central opening of a fastening-element to be embedded in the heel, and a beveled stud projecting into the cavity in opposite relation to the spindle to adapt it to engage a countersunk recess in the fastening-element to hold the latter in place on 105 the spindle.

7. In a mold for cushion-heels, the combination of a bottom-plate having a convex boss for shaping the attaching face of the heel, an upper plate having a cavity for 110 forming the heel, a top-plate for covering the cavity, a shouldered spindle projecting above the boss on the bottom plate to support a fastening-element in predetermined relation to the walls of the cavity, and a 115 projection extending into the cavity from the top-plate and adapted to bear against the fastening-element to hold it in place on its spindle.

In testimony whereof I affix my signature. 120

MAURICE C. CLARK.
